UNITED STATES PATENT OFFICE

2,415,461

SCAFFOLDING

George W. Causey, Pittsburgh, Pa.

Application June 5, 1945, Serial No. 597,615

10 Claims. (Cl. 304—38)

1

My present invention relates to improvements in horizontal supports, such for instance as the stages, used by painters and other workmen, which are supported from above and are lowered as the work proceeds, and also horizontal supports used to bridge spaces in modern sectional scaffolding.

Stages are usually units of ladder-like construction, frequently formed of wood, and more or less standardized as to length, for convenience in handling, and therefore the horizontal extent of the available working surface is limited, and, in instances where such horizontal extent is greater than the length of the unit, the stage and its supporting tackle must be shifted during the job.

Again in modern sectional scaffolding, units formed of metal tubing are in common use and, for convenience in erection and demolition, these units are limited in size, and lack the necessary length of bridge spaces of greater width than that can be spanned by the available units.

The principal object of my present invention is the provision of means for forming horizontal supports, such for instance as painters' stages and scaffold bridges or spans, of greater length than that of the standard units, by combining in end to end relation a plurality of standard units and so reenforcing the combined structure to prevent downward buckling or sagging of the same under load.

For the accomplishment of this object I provide a bridge or connector member into which the adjacent ends of two units are received and secured and a truss structure formed of a post depending from the connector member and across which a cord or cords connected to the outer ends of the two units is tautly stretched.

For the purpose above described I provide a new and improved bridge member provided with sockets into which the ends of the units are received and held.

Other novel features of construction and arrangement of parts will appear from the following description.

In the accompanying drawings wherein I illustrate practical embodiments of the principles of the present invention,

Fig. 1 is a broken plan view of a pair of stage units combined to produce a composite stage.

Fig. 2 is a broken side elevation of the same.

Fig. 3 is a partial longitudinal section of the same on enlarged scale and taken along the dotted line 3—3 in Fig. 1.

Fig. 4 is a perspective view of the bridge member employed to connect the two stage units.

2

Fig. 5 is a cross-sectional view taken along the dotted line 5—5 in Fig. 3.

Fig. 6 is a similar view taken along the dotted line 6—6 in Fig. 3.

Fig. 7 is a fragmentary perspective showing the end portion of one of the units, the left hand one in Fig. 1, with the winch boxing applied thereto.

Fig. 8 is a perspective of the boxing removed from place.

Fig. 9 is a broken perspective of the boxing for the outer end portion of the other unit.

Fig. 10 is a broken plan view showing my invention applied to the formation of a composite support by the union of the abutting ends of two pairs of tubular sectional scaffolding units.

Fig. 11 is a side elevation of the same.

Fig. 12 is a cross-sectional view taken along the dotted line 12—12 in Fig. 10.

Fig. 13 is a perspective view showing one of the terminal cages mounted on the outer end of one pair of units.

Fig. 14 is an end elevation of the same.

Fig. 15 is a detail of the same in side elevation.

Fig. 16 is a perspective showing the other terminal cage in place.

Fig. 17 is a sectional view showing a bridge member for use in connecting single scaffolding units in end to end relation.

Referring first to Figs. 1 to 9 inclusive of the drawings, wherein I illustrate the invention applied to stages, such as painters' flying ladders, 1 and 2 indicate a pair of stages in longitudinal alignment and with their adjacent ends in abutting relation.

The stages are shown as of the standard wooden construction and comprising the longitudinal rails 3 held in parallel spaced relation by the rungs or crossbars 4 to which are nailed or otherwise fastened the longitudinal floor slats 5.

6 indicates the bridge member in which the adjoining end portions of the units are inserted and secured. The bridge is formed by bending or pressing a blank of sheet or plate metal of the proper gauge to provide the requisite strength and rigidity, and is preferably approximately five feet in length. The longitudinal center of the bridge member forms a deck 7 of the proper width to receive the extremities of the stages 1 and 2, and at the lateral edges of the deck 7 the metal is first bent up vertically as at 8, then inwardly horizontally as at 9 and then down vertically as at 10 to form sockets 11 in which the rails 3 of the stage units are telescoped with a sliding fit.

For a distance, for instance, one foot and a

half on either side of the transverse center line of the bridge 6, the inner walls 10 of the sockets are extended to and welded to the deck 7 while, as shown at 10a at either side thereof, the lower portion of the walls 10 are cut away to provide clearance for the end rungs 4 of the stages.

The vertical walls 8 and 10 of the sockets are provided at spaced intervals with bolt holes through which and through registering bolt holes in the rails 3 the stay bolts 12 extend.

The underside of the bridge 6 is provided with a depending post structure 13 over which are tautly stretched the cord members 14, preferably cables, such members being attached to the outer extremities of the stage units 1 and 2.

The post structure may be of any suitable construction. As a convenient and suitable structure I have shown an integral plate comprising two upwardly diverging wings 15 whose upper extremities are flanged horizontally and welded to the under side of the deck 7. At their lower ends the wings are connected by the horizontal portion 16 which is provided with upwardly pressed parallel grooves 17 extending longitudinally of the bridge member 6 and in which the intermediate portions of the cords 14 are nested.

The plate is reenforced by the two brace plates 18 which may be integral and have their apex welded to the under side of the deck, and which diverge downwardly and are welded at their lower ends to the angles between the wings 15 and the horizontal portion 16. Thus there is provided a structure which functions as an inverted king post to form with the cords 14 an under-truss for the composite support.

Suitable removable boxings are provided for the outer ends of the stage units to the attachment and tightening of the cords 14, which preferably are lengths of wire cable. Thus on one of the stage units, illustrated in the drawings as the unit 1, I provide the boxing 19 illustrated in Figs. 7 and 8.

The boxing 19 comprises two parallel rectangular channel members 20 open at the top and of proper dimensions to receive the end portions of the rails 3 of the unit, the inner walls of the channels being downwardly notched as at 21 to provide clearance for the adjacent rung 4 of the unit 1.

The outer ends of the channel members 20 are rigidly connected by the cross plate 22. The walls of the channel members are provided with registering sets of bolt holes 23 and the rails 3 of the unit 1 are provided with registering holes so that stay bolts 24 may be used to detachably mount the boxing 19 on the end of the unit 1. The channels 20 are rigidly connected by the cross brace 25 welded to the bottoms of the channels 20 and under which brace run the cables 14.

The plate 22 is provided with spaced holes 26 through which the ends of the cables 14 extend and are wound around the winch 27 mounted in the box 28 attached to the outer face of the plate 22.

The ends of the shaft upon which the winch is mounted extend through bearing holes in the end walls of the box 28, and one of said ends is squared for the application of a winding handle while the other end is provided with a pawl and ratchet device 29 to prevent accidental unwinding of the winch.

On the outer end of the other stage unit 2 is mounted a similar boxing 30 which is shown in the incomplete perspective of Fig. 10, the same being a substantial duplicate of boxing 19 except

that the box 28 contains two substantial hooks 31 welded to the wall 22 and which are engaged by loops or eyes formed on the cables 14 which extend through the holes 26 in the wall 22.

Referring now to Figs. 10 to 15 inclusive, 32 and 33 indicate two pairs of parallel sectional scaffolding units, each unit comprising a pair of parallel tubular rails 34 permanently connected in spaced relation by the rungs or connecting members 35. The members of each pair of units are shown detachably braced and connected together by the cross braces 36 which are usually formed of rods or tubing of smaller gauge than that of the rails 34. The braces have flattened extremities pierced with bolt holes to fit down over threaded studs extending from the rails and are held in place by wing nuts. The braces are usually crossed to form X-braces with bolts 37 engaging their intersecting portions. The ends 20 of the rails 34 are arranged for pin and socket attachment to the ends of aligned units, one end of a rail being provided with an axially protruding pin and the bore of the tubing at the other end of the rail providing the socket for the pin of an axially aligned rail of an adjoining unit. This form of interconnection is old and well known in the sectional scaffolding art.

The bridge member 38 which I employ to connect together the abutting or adjoining ends of the pair of units 32 to the ends of the units 33, is similar to the bridge member 6 shown on the preceding views for connecting the ends of stages 1 and 2, the bridge member 38 being provided with a like deck 7 and with sockets 11 into which the ends of the units 32 and 33 have a working fit.

However I prefer to have the inner vertical walls 10 of the sockets to extend down to and be welded to the deck 7 for their full length. 40 In case cross braces 36 are employed adjacent the ends of the units 32 and 33 the walls 10 would then be cut away adjacent the ends of the walls, as at 10a in Fig. 3, to provide clearance for the end portions of the cross braces.

45 39 indicates pins or bolts extending vertically through holes in the top walls 9 of the socket and the deck and also through registering holes in the upper and lower rails of the units, to detachably lock the units to the bridge.

50 The underside of the bridge 38 is provided with a depending king post structure 13 similar to that shown in connection with the bridge 6, and over which the cables 14 are tautly stretched, their ends being attached to the outer ends of the units 32 and 33.

55 The outer ends of each pair of units 32 and 33 are held in proper spaced relation by means of the cages 40 which consist of two parallel lengths of tubing of the same gauge as the rails

60 34, bent into a semi-circular curve at their centers to form two parallel legs 41, the legs being spaced apart to register with the rails of one of the units. The two curved members are held in proper spaced relation with their legs parallel 65 by the upper and lower struts 42 which are welded to the upper and lower ends of the curved portions. The ends of the legs are arranged for the usual pin and socket connection with the ends of the rails of the units.

70 At one of the outer ends of the composite support, the left in Figs. 10 and 11, and in Figs. 13, 14 and 15, a pair of vertical bars 43 are mounted in spaced relation on the struts 42, the upper end of the bars being hooked to engage over the top 75 strut and the lower ends of the bars being bifur-

cated to straddle the lower bars, bolts 43a extending through the bars and struts to hold the former in position. Mounted on the bars 43 is a horizontally disposed box 44 having its inner side open, and in said box is mounted a winch 45 upon which the ends of the cables 14 are wound. 46 indicates a pair of horizontal bars connecting the vertical bars 43 between which the cables 14 extend.

The bars 43 of the cage 40 at the other end of the composite support, the right in Figs. 10 and 11, and in Fig. 16, are connected by a brace 47 to reenforce the bars, and looped about the bars are the eyes 48 of the adjacent ends of the cables 14.

In case single units, instead of pairs of units as above described, are to be coupled end to end to form a composite support, I employ a bridge member of less width, such as shown at 49 in Fig. 17, the deck being omitted as unnecessary and the depending king post structure being of substantially the same width as that of the socket 11 and being attached to the floor of the latter. In such case but one tension cord or cable 14 may be used and therefore but one cable groove 17 is provided.

I claim:

1. In a composite support of the character described, the combination of a pair of support units arranged in longitudinal alignment and each comprising a pair of parallel spaced apart longitudinal rails connected together at intervals by cross connections, a bridge member provided along each of its longitudinal edges with socket means in which the adjacent ends of the rails are telescoped, and means to secure said ends in the socket means.

2. In a composite support of the character described, the combination of a pair of support units arranged in longitudinal alignment, each unit comprising a pair of parallel longitudinal members cross connected together in spaced relation, and a bridge member provided with a longitudinal extending socket along each of its lateral edges in which the end portions of the longitudinal members of the units are telescoped, a deck portion connecting the sockets and over which the end portions of the support units extend, and means to secure said longitudinal members to the bridge member.

3. The structure of claim 2 characterized by the cutting away of the lower portions of the inner walls of the sockets adjacent to either end thereof to provide clearance for the cross connection between the longitudinal members of the units.

4. In a composite support of the character described, the combination of a pair of support units arranged in longitudinal alignment, a bridge member provided with socket means in which the inner ends of the units are telescoped, a post member depending from the bridge member, and a tension cord stretched tautly across the bridge member and fastened at its ends to the outer ends of said units.

5. In a composite support of the character described, the combination of a pair of support

units arranged in end to end relation, each unit comprising a pair of parallel longitudinal members cross connected together in spaced relation, a bridge member provided with parallel socket means in which the inner ends of the longitudinal members are telescoped, a post member depending from the socket member, and a tension cord stretched tightly across the post member and having its ends attached to the outer ends of the units.

6. A bridge member, for connecting the ends of a pair of support units arranged in longitudinal alignment, comprising socket means in which the inner ends of the units are telescoped, and a post member depending from the bridge member across which tension cords attached to the outer ends of the units are stretched.

7. A bridge member for connecting the ends of a pair of longitudinally aligned support units each consisting of a pair of parallel longitudinal members held in spaced relation to each other, comprising a pair of parallel socket means in proper spaced relation to receive in telescopic relation the ends of the corresponding longitudinal members of the units, and a deck connecting said socket members to maintain the same in proper relative position and over which the end portions of the support units extend.

8. A bridge member, for connecting the ends of a pair of longitudinally aligned support units each consisting of a pair of parallel longitudinal members held in spaced relation to each other, comprising a pair of parallel socket means in proper spaced relation to receive in telescopic relation the end portions of the corresponding longitudinal members of the support units, a deck connecting said socket members and maintaining the same in proper spaced relation, and a post member depending from the bridge member and across which a tension cord to be attached to the outer ends of the units may be stretched.

9. In a composite support for the purposes described comprising a pair of support units arranged in longitudinal alignment, a bridge member provided with socket means into which the adjacent end portions of the units are telescoped into juxtaposition, a post member carried by the bridge member and normal thereto, and a tension cord stretched across the post member and having its ends secured to the outer ends of the units.

10. The structure of claim 9 characterized by the provision of means mounted on one of the units for regulating the tension of the cord.
